United States Patent Office.

WILLIAM AND C. LEFFINGWELL, OF CLARKSBURG, OHIO.

Letters Patent No. 64,885, dated May 21, 1867.

HOG-HOLDER.

The Schedule referred to in these Letters Patent and making part of the same.

TO ALL WHOM IT MAY CONCERN:

Be it known that we, WILLIAM and C. LEFFINGWELL, of Clarksburg, in the county of Ross, and State of Ohio, have invented a new and improved Hog-Holder; and we do hereby declare that the following is a full, clear, and exact description thereof, which will enable others skilled in the art to make and use the same, reference being had to the accompanying drawings, forming part of this specification.

This invention relates to an improved hog-holder, for ringing, wiring, or snouting, or for slaughtering hogs, and consists of an adjustable box capable of admitting one hog at a time, and of being adjusted to the size of the hog so that he cannot turn, and of holding his head fast in the position required, whereby the dangers and difficulties attendant on the present mode of handling hogs for the above purposes, as well as the injurious effects thereof upon the hogs are entirely obviated.

The accompanying drawing is a perspective view of my improved hog-holder, part of one side being broken out to exhibit the tail-gate and cleats.

A A are two cross-pieces or sills, on which the flooring B is laid, of sufficient length and width to take the largest-sized hog. C C' C' are uprights, bolted to the cross-sills on each side of the floor. The uprights C C' are fixed to the cross-sills and strengthened by the braces C C, and the side planks D are secured upon the uprights C or to the flooring B. The bolts of the upright C' C' serve as pivots or hinges, on which these uprights swing, carrying with them the side planks D' nailed or secured upon them or the uprights C' C', or the side planks D' may be hinged in any other suitable manner to the cross-sills A or to the flooring B. The fixed uprights C carry at or near their top a cross-piece, E, pivoted at e or e', according to the height of the hog, and having secured to them the slats F of equal length with the flooring B. The cross-pieces E are pinned to the hinged or movable uprights C' by pins passing through the pin-holes f f' in the uprights C' and cross-pieces E, respectively, and are adjustable to suit the width and height of the hog. The front end of the box is partially closed by the upright slats G G' attached to the front end of the side planks D D', and by an angling slat, H, secured about half way up the end of the fixed side planks D and stretching across to the top of the hinged or movable side D'. The angling slat is provided with a number of holes, through which passes a rope or cord, R, for the purpose of fastening the hog's snout, or the angling slat may be replaced by a sliding cross-slat furnished in like manner. The front end of the box may also be contracted by narrowing off the flooring B and setting the side planks thereto. The flooring is furnished at its hinder part with the cleats b, against one of which rests a tail-gate, I, made of proper size to fit the box when reduced to its smallest dimensions. The tail-gate I is furnished with a handle, K, which passes between the slats F, and is secured by a pin, L, which enters the pin-holes k arranged in one of the slats F to receive it, the cleats b and pin L keeping the tail-gate in place according to the length of the hog.

The manner in which we use our hog-holder is as follows:

The hogs to be operated on are put in a pen or other enclosed place of convenient size, having a door in it to allow one hog to pass at a time. The box is set to the pen with the back end to the door; the door is opened and the tail-gate removed. One or more of the hogs are driven to the door, when, as the box seems to present a means of escape to the hog, he rushes in, but the front aperture, being contracted by the upright slats G G', the hog can't get out. The tail-gate is then set by placing the lower end in front of one of the cleats on the floor and pressing the handle forwards between the roofing slats and pinning it there according to the length of the hog. The height of the roofing slats and width of the box may now be adjusted as may be necessary to suit the hog, which is now held fast in the box with its snout sticking out in front. The rope or cord is now passed around its snout and the snout drawn up to the angling or cross-piece and tied there. When the snout is wired or the hog otherwise operated on, the rope is loosened from the hog's snout, the pins holding the hinged side taken out, the side let down, and the hog runs out, or his carcass is removed. The box is then reset, another hog driven in, and the operation repeated. The same objects can be obtained, though not so conveniently, by means of a box or trough having fixed sides, but furnished with a tail-gate and contracted front opening. When the roofing slats are dispensed with the tail-gate may be pinned to the cross-pieces E or pinned or hinged to the side planks.

Having thus described our invention, what we claim as new, and desire to secure by Letters Patent, is—

1. The device for holding hogs for the purpose of wiring, ringing, or snouting, or for slaughtering or otherwise operating upon them, adjustable to the size of the hog, in manner and by the appliances substantially as described.
2. The hinged side D' when combined with the hinged roofing E E F F or their respective equivalents, substantially as described.
3. The inclined slat H, or its equivalent, when combined with a box or trough having its front opening contracted by the slats G G', or by an equivalent construction, substantially as described.
4. The tail-gate I, or its equivalent, when combined with a box or trough, having its front opening contracted by the slats G G', or by an equivalent construction, substantially as described.

The above specification of our invention signed by us this 15th day of March, 1867.

WM. LEFFINGWELL,
C. LEFFINGWELL.
